(57) **CLAIM**

The ornamental design for a shaver, as shown and described.

DESCRIPTION

FIG. 1 is a rear elevational view of a shaver showing my new design;

FIG. 2 is a front elevational view thereof;

FIG. 3 is a right side view thereof;

FIG. 4 is a left side view thereof;

FIG. 5 is a bottom plan view thereof;

FIG. 6 is a top plan view thereof;

FIG. 7 is a perspective view thereof;

FIG. 8 is an enlarged view of portion 8 shown in FIG. 1;

FIG. 9 is an enlarged view of portion 9 shown in FIG. 2;

FIG. 10 is an enlarged view of portion 10 shown in FIG. 3;

FIG. 11 is an enlarged view of portion 11 shown in FIG. 4; and,

FIG. 12 is an enlarged view of portion 12 shown in FIG. 7.

In the drawings, the broken lines illustrate portions of the article and enlarged view indicators and form no part of the claimed design.
